UNITED STATES PATENT OFFICE

JOSEPH RABER, OF POPLAR BLUFF, MISSOURI, ASSIGNOR TO DALTON ADDING MACHINE COMPANY, OF ST. LOUIS, MISSOURI, A CORPORATION OF MISSOURI.

ADDING AND RECORDING MACHINE.

1,033,932.

Specification of Letters Patent. Patented July 30, 1912.

Application filed January 17, 1910 Serial No. 536,448.

To all whom it may concern:

Be it known that I, JOSEPH RABER, a citizen of the United States, residing at Poplar Bluff, Missouri, have invented a new and useful Adding and Recording Machine, of which the following is a specification:

This invention relates to recording machines, and more particularly to adding and recording machines, the general object being to provide key mechanism for an adding and recording machine in which the same numeral keys may be utilized for operating the typewriting mechanism or for introducing numbers into the adding mechanism, as desired.

The type of adding and recording machines to which this invention relates is disclosed in an application filed by Hubert 20 Hopkins on January 24, 1903, Serial No. 140,390, and patented in England No. 854 of 1904. In the Hopkins machine, which includes typewriting mechanism having a complete key-board and an adding and recording mechanism having keys separate 25 from the typewriter keys, there is no means for entraining the typewriter numeral keys with the adding mechanism keys.

The object of the present invention is to 30 enable the operator to use the typewriter numeral keys for actuating the typewriting mechanism or for introducing numbers into the adding mechanism, as desired.

A further object is to provide devices 35 whereby the typewriting mechanism will be disabled and held against operation whenever the numeral keys thereof are entrained with the adding mechanism.

Another object is to provide, in combination 40 with a laterally movable paper carriage and typewriting mechanism operable to record any desired data thereon, means for entraining the typewriter numeral keys with adding mechanism registering devices, 45 whereby numbers may be set up or introduced into the adding mechanism, and mechanism for preventing lateral operation of the paper carriage by the typewriting mechanism while said typewriter keys are 50 entrained with the adding mechanism.

There are other objects to be attained by this invention, all of which will appear from the following detail description.

In the accompanying drawings, in which I have shown a satisfactory embodiment of my invention, Figure 1 is a longitudinal section of an adding and recording machine illustrating the key mechanism and the paper carriage, the adding machine devices which do not coöperate directly with the 55 keys being omitted to avoid confusion of the parts. Fig. 2 is a plan view, partially in section, illustrating the connections between the typewriter numeral keys and the adding mechanism keys. Fig. 3 is a detail 60 view of the key mechanism showing the typewriter numeral keys entrained with the levers whereby numbers are introduced into the adding mechanism, and the tabulating key depressed or in use. Fig. 4 is a similar 65 view showing one of the typewriter keys entrained with the adding machine numeral-lever depressed. Fig. 5 is a plan view of 70 one of the coupling or entraining devices whereby the typewriter numeral keys may be utilized for operating the adding mechanism numeral-levers or the typewriter 75 numeral type, as desired. Fig. 6 is a detail view of the portion of the tabulating mechanism coöperating with the paper carriage. 80 Fig. 7 is a detail view illustrating the device controlled by the paper carriage whereby the typewriting mechanism is rendered inoperative whenever the typewriter numeral keys are entrained with the adding mechanism numeral-levers. Figs. 8, 9 and 85 10 are detail views of that part of the tabulating mechanism in the paper carriage whereby said carriage may be released from restraint by the escapement and permitted 90 to move to the proper position for operation of the adding mechanism recording device.

The machine includes a key-board in which the keys 1 are arranged in convenient position upon levers 2 which are pivoted upon a shaft or rod 3, and are upheld in proper position by spring-actuated links 4 having pin-and-slot connection with said levers as shown at 5. The levers of the 95 numeral keys, ten in number, are in two parts, 100

2 both parts of which are pivotally mounted upon the rod or shaft 3. The rear portions of the numeral-levers have pin-and-slot connection with the link 4 in the same manner as do all of the remaining levers. 5 A coupling is provided between the front part and the rear part of each numeral-lever, whereby operation of a numeral key may be caused to effect operation of the entire lever and thereby the entire train of mechanism, effectively to strike the typebars against the platen. These couplings are of 10 duplicate construction, each comprising a sliding block 6 having slots 7 which receive pins 8 on the front portions of the numeral-levers. These blocks are movable longitudinally, and in their rearward position rest over extensions 9 on the rear parts of the numeral-levers as shown in Fig. 1, thus constituting 15 couplings whereby depression of the numeral keys will result in operation of the entire typewriting trains leading from said keys respectively. The complete train of typewriting mechanism in addition to the key mechanism described, includes 20 a series of links 10 pivoted upon a rod or shaft 11 and having pin-and-slot connection 12 with the links 4. The upper ends of the links 10 have links 13 leading 25 to the type bars 14 pivoted upon and supporting rod, 15, preferably in position to constitute a front strike typewriter. It will be noted that the coupling blocks 6 may be moved forwardly beyond the ends 9 30 of the rear portions of the key levers in the typewriter numeral trains, in which position the numeral keys may be operated without affecting the remainder of the typewriter numeral trains. 35

40 The paper carriage 16 is movable laterally, preferably upon anti-friction devices 17, the lateral movement of the paper carriage in operation of the typewriting mechanism being controlled in any known manner through the medium of a pinion 18 meshing with a rack 19 on the carriage. Since the method of stepping the carriage across the machine by operation of the typewriter mechanism constitutes no part of the present invention, such mechanism has not been herein illustrated, it being understood that any suitable type of escapement and carriage moving mechanism may be utilized for these purposes, and it being further understood that the carriage may be actuated by any type of motor, since such devices are old and very well known in the art and may be readily assembled in a machine of this character by anyone familiar with such devices. 55

60 In the advance position of the couplings 6, they are immediately over the upwardly extended ends of adding mechanism numeral-levers 20, pivoted side by side upon a shaft 21, and having their front ends diverging 65 properly, as shown in Fig. 2, so as to terminate alongside of the proper typewriter numeral keys. In the present instance, as in the Hopkins patent and application before mentioned, there are ten numeral-levers 20, one for each of the ten numeral characters. Operation of these numeral-levers is necessary in order to introduce any number into the adding mechanism of the machine. In the Hopkins devices the front ends of the numeral-levers are 70 surmounted by keys arranged adjacent to the typewriter keys and there is no means for preventing operation of the typewriter numeral keys instead of the adding mechanism keys in the listing column. This is the occasion of confusion in many instances, and the operator will not be informed of his error in striking the typewriter numeral keys in the place of the adding mechanism keys until it is too late for correction. These 75 objections are obviated by the mechanism provided for entraining one set of numeral keys with either mechanism as desired, and preventing operation of both mechanisms simultaneously. 80

85 The tabulating key 22 is arranged, in the present instance, at the right of the machine with respect to the operator in alignment with the row of numeral keys, said tabulating key comprising a stem supporting a 90 finger piece and operating in a guide 23, and having its lower end resting upon an arm 24 which is rigid with a rock shaft 25 supported below the key-levers 2. Said rock shaft extends transversely under the 95 key-levers, and at its end opposite from the arm 24 carries a depending arm 26 to which a link 27 is pivoted, the rear end of said link being connected to the vertical arm of the bell crank lever 28, which is pivotally 100 supported at 29. The other arm of said bell crank lever extends forwardly and is pivoted to the lower end of a vertically movable rod 30, the upper end of which extends through a socket 31 supported by the 105 frame of the machine. A spring 32 encircles the rod 30 within the socket 31, abutting at its upper end against the frame of the machine in which the rod 30 has its bearing, and at the lower end against a collar or flange 33 on said rod 30. This spring 110 is effective to actuate the rod 30 downwardly, returning the same and the connected parts including the tabulating key to idle position after each operation. The upper end of the rod 30 is under a bar 34 which is carried by two arms 35 attached to the rock shaft 36 by which the rack 19 is supported. Depression of the tabulating key causes the upper end of the rod 30 to 115 lift the bar 34 and thereby rock the shaft 36 which carries the rack 19 out of mesh with the pinion 18, as shown in Fig. 10. This releases the carriage from the control of the 120 escapement mechanism and permits the mo- 125

tor (not shown) to move the carriage laterally. The lower edge of the bar 34 is provided with a number of projections or shoulders 37, which engage the rod 30 and thereby stop movement of the carriage. These shoulders or projections are formed at proper intervals for column spacing or tabulating, so that after each line of type-writing is completed the carriage may be quickly moved to the proper position for receiving the lists produced by the adding mechanism. Release of the tabulating key permits the rack 19 to be lowered into engagement with the pinion 18, which engagement takes place just before the rod 30 is disengaged from the shoulder 37. The operation of the tabulating key also results in shifting the coupling devices 6, whereby the numeral keys will be connected with the levers 20 and disconnected from the type-writing trains.

A bell crank lever 38 pivotally mounted at 39 has a horizontal arm pivoted to the vertically movable rod 30, and in its depending arm a slot 40 is formed. The lever 38 operates adjacent to a vertical plate 41 in which an angular slot 42 is formed, said slot comprising a horizontal part and a vertical part. 30 43 indicates a bell crank lever pivoted to the plate 41 and having a horizontal arm and a vertical arm. The horizontal arm of said lever 43 is at a slight distance from the vertical arm of the lever 38, and is provided with a slot 44. An axial pin 45 extends through the slots in said levers 38 and 43, and also through the slot 42 in the plate 41, and supports a roller 46 between the said levers 38 and 43. In idle position in which the rod 30 is in its lower adjustment, the levers 38 and 43 occupy the position shown in Fig. 1, in which the pin 45 is at the rear end of the horizontal part of the angular slot 40. When the rod 30 is raised by operation of the tabulating key, the lower end of the lever 38 is moved forwardly until the pin 45 is brought above the vertical part of the slot 42. A vertical rod 47 has its lower end above the plane in which the roller 46 moves, so that when said roller is moved forwardly it passes under said rod. The rod 47 is yieldingly supported by a spring 48 mounted in a socket 49 on the frame of the machine. The upper extremity of the rod 47 carries a roller 50 below a bar 51 on the paper carriage. A cam block 52 is adjustably mounted on the bar 51, having a spring-actuated detent 53 adapted to engage in notches 54 in said bar. By releasing the detent 53 the block 52 may be moved to and latched in any desired adjustment on the bar 51. The specific construction and operation of the block 52 is immaterial, and there are many well known devices capable of use to perform the function of this block.

To adjust the mechanism for operation, so that the machine may be used for type-writing and listing work, the block 52 should be adjusted on the bar 51 so that when the paper carriage is stopped by the rod 30, said block 52 will have passed above and depressed the rod 47, as shown in Fig. 7. This movement of the rod 47 causes the lower end thereof to press upon the roller 46 and thereby operate the lever 43 as shown in Figs. 3 and 4. A link 55 is connected to the lower arm of the lever 43, and has its front end mounted in a suitable support 56, said link 55 is pivoted to an arm 57 attached to a rock shaft 58 which extends transversely, and in the present instance through oblique slots 59 in the levers 20, so that said levers may be free to operate. A series of upwardly extending arms 60 are rigid with the rock shaft 58, there being one of said arms 60 for each of the numeral keys. Links 61 connect said arms 60 with the respective coupling blocks 6. It is apparent that the operation of the lever 43 resulting from the depression of the tabulating key therefore will rock the shaft 58 effectively to shift the couplings 6 forwardly out of engagement with the extensions 9 on the rear members of the typewriter numeral key-levers, and place said couplings above the extensions on the levers 20, as shown in Figs. 3 and 4. Operation of the numeral keys when the couplings are adjusted in this position, will have no effect upon the typewriter trains but will operate the numeral levers 20 effectively to perform their registering functions. The link 55 also carries a projection 62 in front of a transverse rod or bar 63, which is supported by the lower ends of the peculiarly shaped links 64. The rear portions of the typewriter numeral-levers are provided with depending parts 65, while the front portions of said levers are devoid of these projections. The remaining key levers likewise have projections 65, all of said projections being arranged in transverse alignment. Rearward movement of the link 55, as previously described, causes the projections 62 to move the rod 63 beneath the row of projections 65, thereby constituting a lock for all of the typewriter keys except the front portions of the numeral keys which, as stated, are not provided with the projections 65. In this way the entire typewriting mechanism is locked against operation whenever the couplings 6 are adjusted to entrain the typewriter numeral keys with the adding mechanism numeral-levers, and is held against operation so long as the paper carriage remains in position for receiving the lists from the adding mechanism. The links 64 are peculiarly shaped so that the greater portion of their weight is at one side of the pivots, whereby the lower ends of said links will be swung forwardly when released from 130.

engagement by the projections 62 on the link 55.

The typewriter space bar 66 is of usual construction and operation, and the arms of levers supporting said bar also have projections similar to the projections 65, whereby the space bar will be locked against operation whenever the numeral keys are entrained with the adding mechanism. The special keys for the typewriter, such as shift keys, etc., are also locked in the same way.

A spring 67 (Fig. 1) may be employed in connection with the connections leading to the coupling blocks 6, to assist in returning the couplings to position in engagement with the typewriting trains whenever the carriage is returned to position to receive records from the typewriting mechanism. In this way the couplings will be automatically moved to release the numeral-levers whenever the paper carriage is in position to receive typewriting records, and said couplings will entrain the numeral keys with the adding mechanism numeral-levers only when the carriage is moved to position to receive the adding mechanism records by operation of the tabulating key. The typewriting mechanism may be operated to write full lines across the entire sheet of paper, and will be locked against operation only by the tabulating key connections. In ordinary use of the typewriting mechanism it is immaterial what position the block 52 occupies, and said block may depress the rod 47 repeatedly without affecting the connections to the coupling devices, since in normal position of the lever 38, the pin 45 and roller 46 are out of the path of travel of said rod 47, as shown in Fig. 1. This permits said rod 47 to be raised and lowered repeatedly by the movement of the block 52 thereover without in any way affecting the coupling devices on the keys. It is obvious, therefore, that operation of the tabulating key is necessary in order to affect the key-locking mechanism and the coupling devices, and that except when said tabulating key is operated the typewriting mechanism may be operated for any desired purpose without in any way affecting the adding mechanism. The mechanism constructed along these lines enables the use of one set of numeral keys for operating typewriting mechanism or registering numbers in an adding mechanism as desired, the provisions of the tabulating mechanism, the operation of which is necessary in order to introduce numbers into the adding mechanism, simplifies the machine to a great extent and provides an effective safeguard against error, since the locking mechanism controlled by this key will positively disable the typewriting mechanism whenever numbers are being introduced into the adding department of the machine; also the adding department is en-

tirely inoperative so far as the introduction of additional items therein is concerned, whenever the typewriting department is in operation, thus guarding both mechanisms against error.

While I have shown and described a convenient and preferred embodiment of my invention and have made reference to the Hopkins machine, I do not wish to be understood as restricting myself to the specific embodiment described, nor to its use in any specific type of combined adding and typewriting machine, since it will be obvious to those skilled in the art to which this invention relates that there may be various forms of the invention and that it may be used with other types of adding and writing machines than those of the Hopkins construction. I do not restrict myself to its use in any specific sense other than as set forth in the appended claims, but

What I desire to secure by Letters Patent is—

1. In an adding and writing machine, the combination with adding mechanism numeral-levers, typewriting numeral trains including numeral keys and coupling devices, of a tabulating mechanism and means controlled by said tabulating mechanism effectively to operate said coupling devices to disable the typewriting trains and to engage with the adding mechanism numeral-levers, substantially as described.

2. In an adding and writing machine, the combination with adding mechanism numeral-levers and typewriting mechanism numeral keys, of a carriage, tabulating mechanism controlling said carriage, and coupling devices controlled by said tabulating mechanism whereby said typewriting numeral keys may be entrained with said numeral-levers, substantially as described.

3. In an adding and writing machine, the combination with a paper carriage, typewriting mechanism operable to record on paper in said paper carriage, and numeral-levers separate from said typewriting mechanism, of tabulating mechanism controlling said paper carriage, and mechanism controlled by said tabulating mechanism operable to lock the typewriting mechanism against operation, substantially as described.

4. In an adding and writing machine, the combination with typewriting mechanism and a paper carriage, of numeral-levers separate from said typewriting mechanism, and tabulating mechanism controlling said paper carriage operable effectively to entrain said numeral keys with said typewriting mechanism, substantially as described.

5. In an adding and writing machine, the combination with typewriter numeral keys, and numeral-levers separate from said keys, of a carriage, and tabulating mechanism

controlling said carriage and operable to entrain said numeral keys with said numeral-levers, substantially as described.

5 6. In an adding and writing machine, the combination with numeral-levers, numeral keys, and typewriting mechanism entrained with said numeral keys, of tabulating mechanism operable to disengage said numeral keys from said typewriting mechanism and to entrain said numeral keys with said numeral-levers, substantially as described.

10 7. In an adding and writing machine, the combination with a carriage, trains of typewriting mechanism operable to record on paper in said carriage, and coupling devices in said trains, of an adding mechanism, tabulating key controlling said carriage, and devices controlled by said tabulating key effectively to operate said coupling devices 20 to break said trains of typewriting mechanism, substantially as described.

8. In an adding and writing machine, the combination with the adding mechanism numeral levers, and typewriting numeral keys, of a carriage tabulating mechanism controlling said carriage, and devices operable by said tabulating mechanism to entrain said numeral-levers with the typewriting mechanism, substantially as described.

30 9. In an adding and writing machine, the combination with typewriting mechanism, a paper carriage and means holding said carriage, of numeral-levers separate from said typewriting mechanism, tabulating mechanism operable to release said paper carriage, and mechanism operated by said paper carriage effectively to entrain the typewriting mechanism with said numeral-levers, substantially as described.

40 10. In an adding and writing machine, the combination with typewriting mechanism including a paper carriage, and numeral-levers separate from said typewriting mechanism, of tabulating mechanism operating with said paper carriage, and mechanism controlled by said paper carriage and tabulating mechanism operable to disable parts of the typewriting mechanism, substantially as described.

45 11. In an adding and writing machine, the combination with trains of typewriting mechanism, a paper carriage and means holding said carriage, of tabulating mechanism operable to release said paper carriage, and mechanism controlled by said paper carriage operable to disable certain of said trains, substantially as described.

50 12. In an adding and writing machine, the combination with trains of typewriting mechanism, a paper carriage and an escape- 60 ment holding said carriage, of numeral-levers separate from said trains, tabulating mechanism operable to release said paper carriage, and mechanism controlled by said tabulating mechanism and paper carriage

operable to entrain certain of said trains with said numeral-levers, substantially as described.

13. In an adding and writing machine, the combination with trains of typewriting mechanism, a paper carriage, means holding said carriage, and numeral-levers separate from said trains, of tabulating mechanism operable to release said carriage, and automatic devices operable to entrain certain of said trains with said numeral-levers when said tabulating mechanism is operated, substantially as described.

75 14. In an adding and writing machine, the combination with adding mechanism numeral-levers, and typewriting keys, of tabulating mechanism and devices controlled by said tabulating mechanism, whereby said typewriting keys may be entrained with said numeral-levers, substantially as de- 80 scribed.

15. The combination with trains of typewriting mechanism, and numeral-levers separate from said trains, of a paper carriage, means holding said carriage tabulating mechanism operable to release said paper carriage, and coupling devices controlled by said tabulating mechanism and paper carriage effectively to entrain said typewriting mechanism and said numeral-levers when 90 said tabulating mechanism is operated, substantially as described.

95 16. The combination with typewriting numeral keys, a paper carriage, means holding said carriage and adding mechanism numeral-levers, of tabulating mechanism operable to release said carriage, devices controlled by said tabulating mechanism and said carriage effectively to entrain said numeral-levers with said typewriting mechanism, and means operable to lock parts of the typewriting mechanism against operation when said numeral-levers are entrained with the typewriting mechanism, substantially as described.

105 110 17. The combination with the trains of typewriting mechanism including numeral keys, adding mechanism numeral-levers, a paper carriage, means holding said carriage tabulating mechanism operable to release 115 said paper carriage and to couple said typewriting numeral keys and said numeral levers, and mechanism controlled by said tabulating mechanism and said paper carriage operable to lock the trains of typewriting 120 mechanism against operation, substantially as specified.

125 18. In an adding and writing machine, the combination with the typewriting mechanism, and the adding mechanism numeral-levers, of means for rendering said numeral-levers operative, and automatic means for locking the typewriting mechanism against operation when said numeral-levers are operative, substantially as described.

19. In an adding, and writing machine, the combination with normally inoperative numeral-levers and normally operative typewriting mechanism, of mechanism for rendering said typewriting mechanism inoperative and said numeral-levers operative, substantially as described. 55
20. In an adding and writing machine, the combination with trains of typewriting mechanism normally in operative adjustment, and adding mechanism numeral-levers normally in inoperative adjustment, of tabulating mechanism operable to disable said typewriting mechanism and to entrain said numeral-levers with parts of said typewriting mechanism, substantially as described. 60
21. The combination with a carriage, means holding said carriage, and typewriting mechanism, of adding mechanism numeral-levers, means operable to couple a part of said typewriting mechanism with said numeral-levers, and to lock the remaining parts of said typewriting mechanism effectively to prevent operation thereof and means for spacing said carriage incidentally to said coupling operation, substantially as specified. 70
22. In a recording machine, a carriage, trains of numeral recording devices operable to record on paper in said carriage, and tabulating mechanism controlling said carriage, of numeral-levers, and couplings operable by said tabulating mechanism for connecting or coupling said numeral recording devices and said numeral-levers. 80
23. The combination with a carriage trains of recording devices, and separate numeral-levers, of carriage spring mechanism operable to couple said recording devices and said numeral-levers. 90
24. In an adding and writing machine, the combination with mechanism for setting up numbers in the machine, and typewriting mechanism, of means for rendering inoperative one of said mechanisms whenever the other of said mechanisms is operative, substantially as specified. 85
25. In an adding and writing machine, the combination of typewriting mechanism, 95
- mechanism for setting up numbers to be added, and mechanism for rendering either of said mechanisms operative, and as an incident thereto rendering the other inoperative, substantially as specified. 55
26. The combination with trains of typewriting mechanism, numeral levers separate from said trains, and a carriage in which numbers may be set up by the operation of said numeral levers, of a paper carriage, tabulating mechanism operable to position said paper carriage for different vertical columns, and means operated incidentally to the operation of said tabulating mechanism to disable said typewriting mechanism. 65
27. In an adding and writing machine, the combination with typewriting mechanism, a paper carriage, of adding and recording mechanisms, tabulating mechanism operable to position said paper carriage for records to be made by said recording mechanism, and means operated incidentally to said positioning operation to disable said typewriting mechanism. 75
28. The combination with a paper carriage, and trains of recording mechanism operable to record on paper in said carriage, of tabulating mechanism operable to shift said carriage, and means operated incidentally to the shifting of the carriage to break said trains of recording mechanism. 80
29. In a combined typewriting, listing and adding machine, the combination with a paper carriage, typewriting mechanism for recording on paper in said carriage, and listing mechanism for listing numbers on paper in said carriage, of means for rendering said typewriting mechanism inoperative and at the same time render said listing mechanism operable, substantially as specified. 85
- In testimony whereof, I hereunto affix my signature to this specification this 15th day of December, 1909, in the presence of two witnesses.
